US0D1094412S

(12) **United States Design Patent** (10) Patent No.: **US D1,094,412 S**
Oh et al. (45) Date of Patent: ** Sep. 23, 2025

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Sangun Oh**, Suwon-si (KR); **Jaejeong Kim**, Suwon-si (KR)

(73) Assignee: **Samsung Electronics Co., Ltd.**, Suwon-si (KR)

(**) Term: **15 Years**

(21) Appl. No.: **29/936,435**

(22) Filed: **Apr. 9, 2024**

(30) **Foreign Application Priority Data**

Jan. 3, 2024 (KR) 30-2024-0000279

(57) **CLAIM**

The ornamental design for a display screen or portion thereof with graphical user interface, as shown and described.

DESCRIPTION

The sole FIGURE is a front view of a display screen or portion thereof with graphical user interface showing our new design.

The outermost perimeter broken line in the drawing figure depicts a display screen or portion thereof and forms no part of the claimed design.

The remaining broken lines in the FIGURE depict portions of the graphical user interface that form no part of the claimed design.

1 Claim, 1 Drawing Sheet
